UNITED STATES PATENT OFFICE

KARL F. JORSS, OF WASHINGTON, DISTRICT OF COLUMBIA, ASSIGNOR TO CRITTALL CASEMENT WINDOW COMPANY, OF DETROIT, MICHIGAN, A CORPORATION OF MICHIGAN

WINDOW-SCREEN STRUCTURE

Application filed April 8, 1929. Serial No. 353,579.

The invention relates to screen structures associated with windows, preferably of the casement type, and has for its object to provide a frame substantially conforming to the contour of the window casing and adapted to be readily attached to and removed from said casing without the use of tools, said frame carrying an upper and a lower screen member, the upper screen member preferably being fixed to the frame and having its stiles or side members extending to substantially the full length of the frame to constitute guides for the lower screen member, which is vertically slidable thereon, the frame and screen sections being so disposed as to permit free operation of the casement sash or sashes.

The invention is illustrated in the accompanying drawings, in which:—

Fig. 1 is a perspective view, partly broken away, showing the screen carrying frames detachably secured to the window casing.

Fig. 2 is a partial horizontal section of the casement window and screen carrying frame.

Fig. 3 is a fragmentary front elevation of the window casing and screen frame.

Referring to the drawings, 1 indicates the window casing, which is of the casement type, formed of angle irons, on which the sash 3 is pivotally supported by hinges 2, as indicated in Fig. 2. The inner face of the casing 1 is usually finished with a flat surfaced inwardly extending flange 18 against which the sash abuts, when the latter is in its closed position.

Detachably secured to the flange 18 of the window casing is a screen carrying frame 1', generally rectangular in shape and substantially conforming to the contour of the inner face of the flange 18 of the window casing, said frame being formed of channel members having base portions 4 and inwardly extending flanges 5 and 6, the flanges 5 on the stiles or side members of the frame being provided at top and bottom with key hole slots 20, which cooperate with headed studs 19 secured to the inner face of the flange 18 of the window casing, so that the

frame 1' may be readily attached and detached with respect to the window casing by engaging or disengaging the studs 19 and key hole slots 20, without the use of tools.

Preferably rigidly attached to the upper portion of the screen carrying frame 1' is an upper screen section, which is rectangular in shape and of substantially half the area of the frame 1', the rails and stiles of the screen frame being formed of substantially channel shape, by inner flanges 9, base sections 8 and outer flanges 12, which latter, as shown in Fig. 2, are given an inward cant or inclination, so that they will exercise a spring-like effect, for a purpose to be hereinafter explained. The flange 9, which abuts the flange 6 of the frame 1', is provided with a groove formed near its inner marginal edge in which the wire mesh fabric 7 is secured by means of the usual rectangular wire frame 10, which is forced into the groove and also serves to stretch or hold the mesh fabric taut. The flange 12, which extends toward the raised or extruded section of the groove 10, has its end spaced some distance from the projecting groove member to leave a clear opening, which opening in the stiles or side members of the screen frame allows the passage of the runners carried by the lower screen member, as said runners are engaged with the interior of the channel section of the upper screen frame. The stiles of the upper screen section are extended beyond the bottom rail of the said section to substantially the bottom rail of the casing member 1', so that said hollow channel-like stiles of the upper screen section extend for substantially the full length of the screen supporting frame 1'.

The lower screen section is of substantially identical form, as the upper screen section, and comprises a rectangular frame formed of channel sections, indicated at 14, the inner flange being provided with a groove similar to 10 in the upper screen section to receive the wire frame 15 and stretch and secure the wire mesh fabric 13 in said screen frame. Secured to the inner face of the stiles of the

- lower screen section at top and bottom, are runners 16, 16, preferably formed as indicated in Fig. 2 to have a tight sliding fit in the channels formed in the interior of the 5 stiles of the upper screen section, so that the inward cant of the flanges 12 of the stiles will exercise a spring-like pressure on the runners and hold them with a relatively tight sliding fit within the channels of the stiles 10 of the upper screen section, whereby the lower screen section may be adjusted and held in any position by the frictional engagement between the runners and the channelled guides.
- 15 Preferably, a screen carrying frame and the two screen sections are assembled and maintained as a unit to be applied to or detached from the inner face of the window casing in the manner hereinbefore described, 20 so that these units, which are relatively light, may be readily handled by an operative without the use of any tools. In assembling the units, the upper screen section is secured to the outer face of the flange 6 of 25 the frame 1', preferably by spot welding, and the runners 16 carried by the stiles of the lower screen section are engaged with the channel-like members or grooves in the stiles of the upper screen section, so that the 30 lower screen section is carried entirely by and in sliding relation upon the upper screen section and, as indicated, each unit, comprising a screen carrying casing 1 with the two screen sections mounted thereon, is in proper 35 relation for immediate adjustment to the inner face of the window casing by the simple act of engaging the studs 19 in the key hole slots 20. To remove each unit, it is necessary only to raise the unit vertically to 40 bring the enlarged portion of the key hole slots in alignment with the heads of the studs 19 and move the screen carrying frame outward to clear the studs. Some of the salient advantages of this particular coordination are that it may be readily fabricated 45 to conform substantially to any size and shape of window casing to which it may be applied or from which it may be removed without the use of tools, which will effectively 50 screen the window opening and which will permit ready access to the casement sash and its locking and actuating mechanism, which are entirely clear of the screen sections.
- 55 What I claim is:
1. A demountable screen structure for casement windows, comprising a screen supporting frame of channel members conforming to the contour of the window casing, an 60 upper screen member fixed to said frame, a lower screen member slidably mounted on the upper screen member, and means for detachably securing said frame to the casing.
  2. A demountable screen structure for casement windows, comprising a screen support-

ing frame of channel members conforming to the contour of the window casing, an upper screen member fixed to said frame and having its stiles extending to substantially the full length of the frame and constituting 70 guides, a lower screen member slidably supported by said guides, and means for detachably securing said screen supporting frame to said casing.

3. A demountable screen structure for casement windows, comprising a screen supporting frame of channel members conforming to the contour of the window casing, an upper screen member fixed to said frame and having its stiles extending to substantially the 75 full length of the frame and formed as channel guides, a lower screen member having runners on its stiles engaging said guides, and means for detachably securing said screen supporting frame to said casing.

4. The combination with a window casing, 80 of a screen supporting frame of channel members conforming to the contour of the casing, upper and lower screen members, the former fixed to the frame and the lower 90 member slidably supported by the upper member, and stud and slot connections between the casing and the screen supporting frame.

5. The combination with a window casing, 95 of a screen supporting frame of channel members conforming to the contour of the casing, upper and lower screen members, the former fixed to the frame and the lower member slidably supported by the upper 100 member, headed studs carried by the window casing, and key hole slots formed in the frame cooperating with said studs for detachably connecting the frame to the casing.

In testimony whereof I affix my signature. 105
KARL F. JÖRSS.
